UNITED STATES PATENT OFFICE.

WALTER LABURDA, OF COALTON, OKLAHOMA.

GRINDING-MILL.

1,366,391.

Specification of Letters Patent. Patented Jan. 25, 1921.

Application filed April 13, 1920. Serial No. 373,638.

To all whom it may concern:

Be it known that I, WALTER LABURDA, citizen of Poland, residing at Coalton, in the county of Okmulgee and State of Oklahoma, have invented certain new and useful Improvements in Grinding-Mills, of which the following is a specification.

This invention relates to a grinding mill intended more particularly for grinding grains such as corn, oats, wheat, barley or other grains, the invention having more particular reference to a portable grinding mill adapted for hand operation.

The invention has for an object to provide a simple and inexpensive grinding mill of the above type having a novel arrangement of driving means for driving the rotary grinding element at various speeds, and new and improved arrangement of the grinding surfaces.

For further comprehension of the invention, and of the objects and advantages thereof, reference will be had to the following description and accompanying drawings, and to the appended claims in which the various novel features of the invention are more particularly set forth.

Figure 1 of the drawings is a vertical sectional view of a grinding mill constructed according to the invention, this view being taken on the line 1-1 of Fig. 2.

Fig. 2 is a horizontal section on the line 2-2 of Fig. 1.

Fig. 3 is a horizontal section on the line 3-3 of Fig. 1.

Fig. 4 is a detail perspective view of the rotary grinding member.

As here shown the casing of my improved grinding mill is formed by a hollow wooden block 10 supported on legs 11, this block being here of rectangular shape in horizontal section and provided with a circular chamber 12 open at the top.

Within the bottom of this chamber is supported the lower stationary grinding member 13 and above this stationary member is mounted the rotatable grinding member 14, these members jointly filling the chamber 12 and being made of any usual or approved material. The upper member 14 is supported clear of the lower member by means of a screw 15 which is threaded upwardly through the base of the casing 10 and passes freely through a suitable axial

aperture in the lower member 13, and is formed with a conical upper end 15' which engages in a suitable socket 16 formed on the underside of a spider 17 which extends across the lower end of an axial feed opening 18 in the upper grinding member, a lock nut 19 serving to lock the screw in adjusted position.

A funnel 20 projects upwardly from this feed opening to a point just under the open lower end of a hopper 21. The hopper 21 is supported above the grinding members by means of a pair of bars 22 which are fixed at their upper ends to one of the side walls of the hopper and have vertically slotted lower ends 22' which extend downwardly across the face of the block 10 and are adjustably secured to the latter by means of the wing-headed screws 23 passing through the slots in the bars and threaded into the side wall of the block 10, headed pins 24 carried by the block and projecting through the slots in the bars serving to guide the latter during adjustment.

The means which I have designed for rotating the upper grinding member 14 is as follows:

Mounted on the upper end of the member is a large gear 25 which may be held against rotation by being fitted over a square boss 26 on the upper end of this member. This gear meshes with a series of four smaller gears 26, 27, 28 and 29 located at diametrically opposite sides thereof and suitably journaled on top of the block 10, the gears 26, 27 and 28 being of different sizes, the gear 29 being simply an idler forming a side bearing for the grinding member 14. The gears 26, 27, and 28 are adapted to be engaged as desired by a large crown gear 30, means being provided on each side of the block to removably support the crown gear in engagement with the desired one of equal sized pinions 31 fixed co-axially to the small gears, the crown gear having a crank 32 fixed thereon for manual rotation.

As here shown a series of pintles 35 are fixed in the side walls of the block 10 and project outwardly therefrom, being preferably formed with enlarged headed bodies 36 which extend through the walls of the block and have nuts 37 threaded on their

outer ends against the outer surfaces of the block. The gear 30 is mounted loosely on the pintle 35 and is retained against displacement by a locking yoke 38 whose legs 5 engage in notches 39 on the pintle, a pin 40 preventing disengagement of the yoke from the pintle. As will be obvious the grinding member 14 will be driven at varying speeds for a given rotation of the gear 30 according to which one of the pintles the latter is mounted on.

Referring now to the grinding surfaces and discharge means a chute 42 leads downwardly and outwardly through one of the 15 side walls, the lower edge of the chute opening to the chamber 12 being just below the upper surface of the lower grinding element. The ground grain may be discharged through the chute to any suitable receptacle 20 such as that indicated at 43.

Formed in the upper surface of the grinding member 13 is a spiral groove 44 whose outer end registers with the top of the chute 42 so that the ground material works 25 through this groove to this chute. The lower surface of the upper grinding member 14 is formed with a series of radial 30 grooves 45 and it will be apparent that the construction of the co-acting grinding surfaces causes both a shearing and crushing action to take place on the material and increases the efficiency of the grinding mill.

Having thus described my invention what I claim as new and desire to protect by Let-

ters Patent of the United States is as follows:

1. A device of the class described comprising a member to be rotated, a rectangular casing supporting said member, a gear fixed to said member co-axially therewith, a series of gear elements spaced around said first gear in engagement therewith and mounted on the top of said casing adjacent the sides thereof, a manually rotatable gear, and means provided on different sides of said casing for supporting said manually rotatable gear in engagement with any desired one of said gear elements, the respective gear elements having different transmission ratios.

2. A device of the class described comprising a member to be rotated, a rectangular casing supporting said member, a gear fixed to said member co-axially therewith, a series of gears of different sizes spaced around said first gear in engagement therewith and mounted on the top of said casing adjacent the sides thereof, a series of pinions fixed co-axially to the respective ones of said series of gears, a series of pintles 60 projecting from the different sides of the casing, and a manually rotatable gear adapted to be removably mounted on either of the said pintles in engagement with either of the said pinions.

In testimony whereof I have affixed my signature this 5th day of April 1920.

WALTER LABURDA.
